UNITED STATES PATENT OFFICE

CLIFFORD TRAUT, OF NEWPORT, KENTUCKY, ASSIGNOR TO THE HIGGIN MANUFACTURING COMPANY, OF NEWPORT, KENTUCKY, A CORPORATION OF WEST VIRGINIA

PROTECTIVE AND CONTROLLING DEVICE FOR ROLLING WINDOW SCREENS

Application filed September 11, 1931. Serial No. 562,316.

My invention pertains to the art of rolling window screens, wherein, as is well understood, there is provided at the sides of a window opening a pair of guides, and at the top of the window opening a spring roller upon which the screen cloth is wound as it is taken up. The roller is usually in an appropriate housing; and there is provided a draw bar extending across the window opening and riding in or along the guides. One end of the screen cloth is attached to this draw bar, the other end, of course, being attached to the spring roller. As the draw bar is brought down along the guides, the screen cloth is unrolled from the spring roll, and when the draw bar is locked in its lowermost position the screen cloth completely covers the window opening. A suitable latching means is provided for the draw bar. The edges of the screen ride in the side guides.

For window openings of moderate size, this construction alone has been found adequate, but where the window opening is very large the pressure of air against the screen cloth either from the inside or the outside of the building, is frequently sufficient to cause the screen to bulge inwardly or outwardly, to an extent permitting it to come out of the side guides. Under these circumstances the screen fails of its function, and the operator has the inconvenience of manually inserting the cloth back into the guides.

In my prior Patent No. 1,833,140, Nov. 24, 1931, I have described a construction in which bars or reinforcing members, separate from the screen cloth, are provided with means sliding in the side guides. These bars are held at different predetermined heights by a series of stops. As the draw bar is raised, feet on the draw bar engage these bars and lift them, one after another, until the window opening is clear.

My present invention is an improvement upon this structure, wherein it is my object to provide means for adjusting the bars transversely of the window opening so as to insure their proper co-operation with the stop members, an improved interengagement of means on the bars with a particular character of side guide construction, and means whereby

not only are the bars irremovably associated with the side guides throughout the extent of the operation of the screen, but also are more positively guided in their movements, and prevented from assuming improper positions.

Also it is my object to provide means for installing my controlling features in screens already in use, or in adding or taking out bars, all without disassembly of the screen.

These and other objects of my invention which will be set forth hereinafter or will be apparent to one skilled in the art upon reading these specifications, I accomplish by that certain construction and arrangement of parts of which I shall now describe a preferred embodiment, reference being had to the accompanying drawings, wherein:

Figure 1 is an elevation of a typical window opening fitted with my improved screen.

Fig. 2 is a sectional view therethrough taken along the lines 2,2 in Fig. 1.

Fig. 3 is a plan view of the device by which my reinforcing and screen controlling bars are mounted with reference to the side guides.

Fig. 4 is a sectional view of an exemplary bar taken along the lines 4,4 of Fig. 5.

Fig. 5 is a front view of one of my bars. Figs. 6 and 7 are perspective views of one form of stops which I may employ.

It will be understood that my invention is not restricted to the controlling of rolling window screens. It may be used in the controlling of shades, light-tight curtains, screens and the like, and in fact, in any situation in which a flexible closure member is mounted for sliding contact with interspaced guiding members, where it is necessary to reinforce or control the flexible member without directly attaching thereto or incorporating therewith, reinforcing members.

I have illustrated in Fig. 1 an exemplary window opening having a sill 1, jams 3, and a top 5. Behind this top in the particular embodiment illustrated, there is mounted a spring roller for the control and retraction of the screen cloth 6. The spring roller may be of any of the known types, and need not be particularly described by me. Fastened on the jambs of the window I have shown side

guides 7 and 8, which will be more particularly described hereinafter, and which have channels in which the edges of the screen cloth 6 slide. The lower end of the screen cloth is fastened to a draw bar 9, which may 5 have a flange 10 adapted to be engaged by the fingers in manipulating the draw bar. Latches 11 and 12 may be provided in the form shown, or any other suitable forms, the 10 purpose of which is to hold the draw bar down by engagement with other latching members 13 and 14, upon the side guides, or elsewhere.

At intervals up the window space I have 15 shown controlling or reinforcing bars 15 and 16. These bars prevent the screen from sagging as aforesaid. They may be located either inside or outside of the window space, or upon both sides of the screen cloth if desired. They are slidably mounted with respect to the guides 7 and 8, so that as the draw bar 9 is raised to the position shown in the dotted lines, Fig. 1 these bars will be moved by the draw bar itself, or by feet 17 20 and 18 thereon, to slide with the draw bar to the top of the window space, where they also are shown in dotted lines. If the draw bar be again lowered to the bottom of the window space, the bars 15 and 16 will descend with it until they selectively engage 25 certain stops upon the window jambs, or upon the guides. The bar 16 has been shown as longer than the bar 15, and resting upon stops 19 and 20, which are relatively narrower 30 and past which the shorter bar 15 can slide 35 during its descent along the guides. The bar 15 is shown resting upon stops 21 and 22, which are wider than the stops 19 and 20, and which therefore serve to support the 40 bar 15.

I have shown the window as having on its inner side two bars 15 and 16. It may have a greater or lesser number, as desired. Ordinarily, quite irrespective of the width of the 45 window, a reinforcing bar every thirty inches of the length of the window opening, will be found sufficient with screen cloth, excepting perhaps, in localities characterized by very high winds. The width of the window 50 has a great deal to do, of course, with the tendency of the screen cloth to come out of the guides, but ordinarily bars every thirty inches will serve to retain the screen cloth quite irrespective of the width of the window 55 opening. Where more than two bars are employed, they will be arranged as to their lengths to operate selectively with appropriate stop means after the manner illustrated in Fig. 1. Thus the bars will become progressively shorter toward the bottom of the window space, and the stop means will become progressively wider, or be otherwise positioned so as to catch the bars selectively.

In the preferred form of my invention I 60 provide means whereby the bars cannot,

without disassembly of the parts, be removed from engagement with the side guides, excepting past the ends of these guides. When this is done, there will be no chance of the bars falling out of the construction, since the 70 guides themselves extend over the window sill to and sometimes into the housing which surrounds the spring roller. This feature has a number of advantages, among which is this: That even though the bars become 75 somewhat canted during the lowering of the draw bar, they nevertheless cannot fall out of the window opening. Another advantage is that the particular means of my invention may be used also to adjust the bars with reference to their path of travel along the 80 guides, so as to insure the proper co-operation of the ends of the bars and the stop devices. Finally, my invention provides for some angular play in the bars as may be 85 necessary for their satisfactory operation, and at the same time prohibits such an angularity as would prevent the bars from coming to rest upon the proper stop means.

It will be understood that the side guides 90 present a channel in which the edges of the screen cloth slide, and it will be further understood that my bars will, in any event, have members which enter this channel, or at least another vertical channel in a suitable device. It would be possible, of course, to provide 95 separate guides for the bars, but this not only is unnecessary, but is expensive. I shall describe as my exemplary construction one in which the bars have means entering the 100 channel of the screen guide. The outer ends of the bars may also abut the guides, and have a supplementary motion-controlling function. However, if a member on the bars merely enters the slot aforesaid, it will not 105 serve to prevent the endwise withdrawal of the bars from engagement with the screen 110 guide. When a bar becomes canted, there is a tendency for this endwise withdrawal, and when this occurs the bar will be freed 115 from the channel and may fall upon the operator. Consequently, it is necessary to provide means whereby the member entering the slot, or otherwise co-operating with the 120 guide, has a non-withdrawable interengagement therewith, which interengagement does not, however, impede the sliding of the member along the guide. To this end, I provide a type of guide in which at least one side of the channel is defined by a portion of the wall 125 of the guide which is reversely bent; and I provide to co-act therewith, a member on the bar to enter the guide and extend beyond the edge of the inturned wall, and then by means of a return bend, or the like, to engage behind said wall.

I have shown in Fig. 2 a guide having side walls 23 and 24, and a slot indicated at 130 25, which is defined by inturned portions 26 and 27 of the guide walls, which inturned

members are spaced, as shown, from the outer walls. In the particular instance shown, the guide is made of one piece having a back portion 28 wider than the guide itself, directly connected to the wall 23, and connected to the wall 24 by a turned over portion 29, which provides a convenient attachment flange through which screws, or other devices, may be placed in securing the guide to the window jamb.

My bars may comprise solid or hollow members preferably, though not necessarily, of metal. I have indicated in Fig. 4 a bar formed of sheet metal bent to provide a face 30, and sides 31, the bar thus being of substantially channel shape, but having upon its rear side turned over reinforcing ears 32. The bar, where it approaches the guides, may be, and preferably will be, cut away as at 33 to accommodate the guides and to permit the back portions 32 to be approached as closely as possible to the screen cloth itself, preferably without actually touching the same. A sliding mounting member for the bars is illustrated in elevation in Fig. 3, and in plan in Fig. 2. It comprises a foot 34 adapted for attachment to the bar itself, an angularly bent portion 35, and a portion 36 adapted to enter the guide through the wall 50 therein. The portion 36 is substantially parallel to the foot 34, from which it is offset by the angularly bent portion 35.

The portion 36 is reversely bent at its end to provide a member 37 spaced slightly therefrom, the function of which is to ride in the guide behind the turned over portion 27 of the guide wall. This relationship is illustrated in Fig. 2. It will be evident that my mounting member may not be withdrawn from the guide in any transverse direction. It can only be removed from the guide by being withdrawn from an end thereof.

The turned over portion 37 of each mounting means has its end 38 biased at angle of about 45 degrees with its lateral edges. It will be noticed that although there is preferably an appreciable space between the bend 36a of the mounting device and the inner edges of the turned over wall 27 of the guide, yet the end of the portion 37 of the mounting member approaches in use quite closely to the inner edge of the pocket between guide members 27 and 24. Therefore, were it not for the bevel 38, the bar 16 would bind on the guides as soon as it had canted by a very small degree. The bevel permits the canting of the bar to a useful degree without causing it to bind, while the relatively close fit of the end of member 37 in the end of the guide pocket between walls 27 and 24 permits my mounting members to be used to center the bars 16 and adjust them relative to the stop means, as will hereinafter be explained. Since, however, provision must be made for the canting of the strip in both directions, it is necessary for

me to make the mounting members illustrated in Fig. 3 in the form of rights and lefts, that is, when in their operating positions they have their biased ends slanting upward and out toward the respective sides of the window. As shown in Fig. 1, upper right, my mounting member shown in Fig. 3, may be slipped under the top member 5 and over the top of and into the guide on that side of the window; the bevel 38 on the lower corner of my mounting members enabling these members to clear the guides during this insertion. This construction also enables me to install additional bars without dismantling the entire structure.

The portion 34 of my mounting member is perforated as at 39, and has a return bent part 34a enclosing an ordinary nut 40, held from turning thereby. A slot 41 is cut in the face 30 of my bars within the ends thereof, admitting a bolt or screw 42 to screw into the nut 40, in the relationship shown in Fig. 2, to fasten my mounting device to the bar. The slot 41 provides for the adjustability of my mounting member with respect to the bar, and in this way the bar may be centered in the window opening and positioned in such a way as to cooperate properly with stop members 19 and 20, or 21 and 22.

These stop members may conveniently be in the forms of blocks of metal, which may be held against the jamb by screws. In some forms of the apparatus, and particularly where the guide is made in two parts rather than in one part, it may be found advantageous to connect the stops directly to the guide, as by spot welding, or otherwise. Where the guide is not one piece, spot welding these stops against the guide is difficult, and other methods of attachment, such as soldering, are likely to be rendered ineffective by heat treatments employed in finishing the guides. The attachment of the stops to the jambs directly is usually entirely satisfactory.

My bars 15 and 16 may be located upon either side of the screen cloth, or upon both sides thereof, particularly where conditions of fluid pressure of both sides are to be expected. I have shown in dotted lines in Fig. 2 another bar 16a lying upon the outer side of the screen space. Such a bar or series of bars will, of course, have its own series of stop mechanisms, and an appropriate set of feet or other raising means upon the draw bar 9.

Modifications may be made in my invention without departing from the spirit thereof.

Having thus described my invention, what I claim as new and desire to secure by Letters Patent, is:—

1. In a protective device for a rolling closure, spaced side guides having channels, a bar movable along said guides, and having means entering said channels, said bar being unattached to said rolling closure, said means entering said channels having a portion with-

in said guides to prevent the withdrawal thereof through said channels.

2. In a protective device for a rolling closure, spaced side guides having channels, said 5 rolling closure having its edges operating in said channels and having a draw bar, and a bar separate from said draw bar and said closure means, and having mounting means entering the channel of a guide, and bearing 10 at its end in said guide, and means for preventing the withdrawal thereof through said channel.

3. In a protective device for a rolling closure, spaced side guides having channels, said 15 channels defined upon at least one side by a re-entrant portion of the guide wall, and a bar unattached to the closure member of said roller closure, and having mounting means with a portion extending through said channel and engaged beyond the re-entrant portion 20 of said wall.

4. In a protective device for a rolling closure, side guides having re-entrant spaced walls defining a channel, whereby a rolling 25 closure member may have its edges riding in the channels of said guide, and have a draw bar slideable with respect to said guides, and a bar unattached to said draw bar or said rolling closure, and having a member entering the slots of said guides and turned over 30 on the outer side of said re-entrant walls to prevent withdrawal thereof through said channels.

5. In a protective device for a rolling 35 closure, side guides having reversely bent interspaced walls defining a channel, whereby a rolling closure member may have its edges riding in the channels of said guide, and have a draw bar slideable with respect to said 40 guides, and a bar unattached to said draw bar or said rolling closure and having a member entering the slots of said guides and turned over behind said reversely bent walls to prevent withdrawal thereof through said 45 channels, and means for adjustably attaching said slot-entering member to said bar.

6. In a protective device for a rolling closure, a guide having a channel defined by at 50 least one re-entrant wall, a bar unattached to said rolling closure, said bar of a length to have its ends overlap said guide, and mounting means adjustably attached to said bar, said mounting means comprising an attached portion and a portion in offset relationship 55 for entering said channel, said latter portion having a reversely bent member at the end thereof.

7. In a protective device for a rolling closure, a guide having a channel defined by at 60 least one re-entrant wall, a bar unattached to said rolling closure, said bar of a length to have its ends overlap said guide, and mounting means adjustably attached to said bar, said mounting means comprising an attached portion and a portion in offset re- 65

lationship for entering said channel, said latter portion having a reversely bent member at the end thereof, said reversely bent member being beveled at its end.

8. In combination with a hollow bar having 70 a sidewise disposed cut-away portion, mounting and guiding means having an attachment foot, an angularly bent portion connected therewith, and a sliding portion maintained by said angularly bent portion in offset relationship with said foot, said sliding portion having a reversely bent portion.

9. In combination with a hollow bar having 75 a sidewise disposed cut-away portion, mounting and guiding means having an attachment foot, an angularly bent portion connected therewith, and a guiding portion maintained by said angularly bent portion in offset relationship with said foot, said sliding portion having a reversely bent portion, and being adapted to coact with a guide having outer walls, and a channel at least one side of which is defined by a reversely bent portion of one of said walls, said reversely bent portion of said mounting device being 80 adapted for engaging behind said reversely bent portion of said guide.

10. In combination with a bar having a terminal attachment portion with an opening therethrough, mounting and guiding means having a foot of U-shape lying along 85 said attachment portion, a nut held in the U-shaped foot and engaging a side of said foot so as not to turn therein, and a fastening element extending through said opening and 90 screwed into said nut.

11. In a protective device for a rolling closure, guides for the opposite edges of the closure, each having a channel opening toward the respective closure edge, said channel having a hooked edge, a bar unattached to said closure with its end portion adjacent to the respective guides, and mounting means detachably secured to the respective end portions and having hooked parts entering the 100 respective channels and hooking into said hooked edges of said channels, the end of the hooked part at each side being biased outwardly and upwardly.
